Primary Examiner — Cynthia R Underwood*(74) Attorney, Agent, or Firm* — Rumit Ranjit Kanakia(57) **CLAIM**

We claim the ornamental design for a cable clip, as shown and described.

DESCRIPTION

FIG. 1 is a Perspective view of a cable clip showing my new design in open position;

FIG. 2 is Front view thereof;

FIG. 3 is Back view thereof;

FIG. 4 is a Right-side view thereof;

FIG. 5 is a Left-side view thereof;

FIG. 6 is a Top view thereof; and,

FIG. 7 is a Bottom view thereof.

The broken lines in the drawings depict portions of the cable clip that form no part of the claimed design.
